(57) **CLAIM**

The ornamental design for a solar charging station, as shown and described.

DESCRIPTION

FIG. 1 is a perspective view of a charging station according to an embodiment of my design;

FIG. 2 is a front view of the charging station shown in FIG. 1;

FIG. 3 is a rear view of the charging station shown in FIG. 1;

FIG. 4 is a left side view of the charging station shown in FIG. 1;

FIG. 5 is a right side view of the charging station shown in FIG. 1;

FIG. 6 is a top plan view of the charging station shown in FIG. 1; and,

FIG. 7 is a bottom view of the charging station shown in FIG. 1.

The broken line portions of the figure drawings are included to show unclaimed subject matter only and forms no part of the claimed design.

1 Claim, 4 Drawing Sheets
